UNITED STATES PATENT OFFICE.

CHARLES J. SCHENK, OF RUMMINGTON, CALIFORNIA.

DOUBLE-ACTING PUMP-HEAD.

1,322,470.

Specification of Letters Patent. Patented Nov. 18, 1919.

Application filed April 3, 1919. Serial No. 287,191.

To all whom it may concern:

Be it known that I, CHARLES J. SCHENK, a citizen of the United States, residing at Rummington, in the county of Kern and State of California, have invented new and useful Improvements in Double - Acting Pump-Heads, of which the following is a specification.

My object is to make a long stroke double acting pump head providing a continuously uniform flow, and my invention consists of the novel features herein shown, described and claimed.

Figure 1 is a side elevation of a double acting pump head embodying the principles of my invention, as seen looking in the direction indicated by the arrows 1 in Figs. 2 and 3.

Fig. 2 is a front elevation as seen looking in the direction indicated by the arrow 2 in Fig. 1.

Fig. 3 is a rear elevation as seen looking in the direction indicated by the arrow 3 in Fig. 1.

Fig. 4 is an enlarged perspective showing the mutilated gears and gear racks.

Fig. 5 is a fragmentary sectional detail of the upper mutilated gear shown in Fig. 4 and showing one of the spring catch teeth.

The base 1 is rectangular in plan and supports the upper end of the pump casing 2, and the spout 3 leads the liquid from the pump casing 2. Posts 4 and 5 are rigidly mounted upon one side of the base 1, and similar posts 6 and 7 are rigidly mounted upon the other side of the base 1.

A brace 8 connects the upper ends of the posts 4 and 5, a brace 9 connects the intermediate portions of the posts, and a brace 10 connects the lower ends. Similar braces connect the posts 6 and 7 together. A brace 11 connects the intermediate parts of the posts 4 and 6 together, and a similar brace 12 connects the intermediate parts of the posts 5 and 7 together.

Guide rollers 13, 14 and 15 are mounted between the upper ends of the posts 5 and 7 upon a spindle 16. Similar guide rollers 17, 18 and 19 are mounted some distance below the spindle 16 upon a spindle 20. The rollers 15 and

19 are in a vertical line, the rollers 14 and 18 are in a vertical line, and the rollers 13 and 17 are in a vertical line.

The inner pump rod 21 works inside of the outer pump rod 22, and the lower pump rod 22 works through a stuffing box construction 23 fixed at the upper end of the pump casing 2. A gear rack 24 is connected to the upper end of the inner pump rod 21 by clamps and bolts 25. The gear racks 26 and 27 are connected to the upper end of the outer pump rod 22 by clamps and bolts 28. The gear racks 24, 26 and 27 are slightly spaced apart and in a straight line. The back smooth side of the gear rack 24 runs in the rollers 14 and 18, and the back smooth sides of the gear racks 26 and 27 run in the rollers 13 and 17 and 15 and 19. The gear teeth of the racks are at the opposite sides from the smooth sides which run upon the rollers, the rollers serving to hold the racks in their proper tracks to mesh with the mutilated gears.

The lifting shaft 29 is mounted in the braces 9, a drive pulley 30 is fixed upon the outer end of the drive shaft, the mutilated gear 31 is fixed upon the lifting shaft 29 in line with the gear racks, said mutilated gear having a segment 32 meshing with the gear rack 24, and segments 33 and 34 meshing with the gear racks 26 and 27. A driving shaft 35 is mounted in the braces 9 parallel with the lifting shaft 29, and a long faced pinion 36 is fixed upon the driving shaft 35 to mesh with the mutilated gear 31. The segments 32, 33 and 34 form a continuous gear in mesh with the long faced pinion 36. A pinion 37 is fixed upon the driving shaft 35 in a plane at one side of the gear racks. An idler gear 38 is mounted upon an idler shaft 39, said idler shaft being mounted in bearings near the upper ends of the posts 4 and 6 and the idler gear 38 meshing with the pinion 37, and a gear 40 meshes with the idler gear 38. A gear 40 is fixed upon one side of the mutilated gear 41 by bolts 42 extending through slots 43, so that the gear 40 may be adjusted relative to the mutilated gear 41 to the limits of the slots. The mutilated

100

gear 41 is mounted upon a shaft 44 and the shaft is mounted in bearings at the upper end of the posts 4 and 6. The mutilated gear 41 has a segment 45 adapted to mesh with the gear rack 24 and segments 46 and 47 adapted to mesh with the gear racks 26 and 27.

The lifting shaft 29 carrying the mutilated gear 31 moves in the direction indicated by the arrow 48, and the driving shaft 35 carrying the gears 36 and 37 moves in the opposite direction as indicated by the arrow 49, and the idler gear 38 meshing with the gear 37 goes in the direction indicated by the arrow 50, and the mutilated gear 41 moves in the direction indicated by the arrow 51 so that the mutilated gear 31 moves in the opposite direction from the mutilated gear 51.

20 There is a break 52 between the ends of the segment 32 and breaks 53 and 54 between the ends of the segments 33 and 34. In a like manner there is a break 55 between the ends of the segment 45 and breaks 56 and 57 between the ends of the segments 46 and 47. The racks 26 and 27 serve the purpose of a single rack, the object being to divide the strain and balance the pull upon the outer pump rod 22, and in a like manner the segments 33 and 34 and the segments 46 and 47 serve the purpose of single segments. The gears and racks are set and timed so that the mutilated gear 31 drives the racks 24, 26 and 27 upwardly and the mutilated gear 41 drives the racks downwardly, and so that when the segment 31 is in mesh with the rack 24 and driving the rack 24 upwardly to raise the pump rod 21 the segments 46 and 47 are in mesh with the racks 26 and 27 and driving the racks downwardly to lower the outer pump rod 22, and when the segment 32 reaches the end of the down stroke the segment 35 takes hold of the rack 24 and starts the upstroke of the inner pump rod 21, and in a like manner when the segments 33 and 34 reach the upstroke of the racks 26 and 27 the segments 46 and 47 take hold and start the down stroke.

Breaks 58 and 59 are formed in the racks 26 and 27 between the teeth 60 and 61 which mesh with the segments 33 and 34 and the teeth 62 and 63 which mesh with the segments 46 and 47. Bevel faced spring catch teeth 64 extend from the ends of the segments 46 and 47 to fit in the breaks 58, and a double width tooth 65 is formed directly behind each catch tooth to fit in the break 59 to avoid the shock which would otherwise result when the segments 33 and 34 run out of mesh and the segments 46 and 47 run into mesh, thereby reversing the motion of the racks. In a like manner a bevel faced spring catch tooth 66 and a wide space 67

is formed at the end of the segment 45 to mesh with the corresponding breaks in the rack 24.

Referring to Fig. 5, a recess 68 is formed from the peripheral face of the casting forming the rack 47 and at the forward end of the rack, a bore 69 extends inwardly from the recess 68, and a second bore 70 extends inwardly from the bore 69. The bevel faced spring catch tooth 64 fits in the recess 68, a spring 71 fits against the back of the tooth 64 in the bore 69, and a stem 72 extends from the back of the tooth 64 through the spring 71 into the bore 70. A pin 73 extends through the body and through a slot 74 in the tooth 64 to limit the outward movement of the tooth.

At the time the rack 27 is being lifted by the rack 34 and is about at the end of its upward movement the mutilated gear 41 is moving in the direction indicated by the arrow 75, and the rack 27 is moving in the direction indicated by the arrow 76, and the segment 34 is about to let go of the rack, and then as the spring catch tooth 64 passes the double width tooth 77 formed between the breaks 58 and 59 the tooth 64 will be pressed inwardly against the tension of the spring 71 and snap behind the tooth 77 into the break 58 to hold the rack 27 from falling when the segment 34 lets go. Then continued action will bring the tooth 65 into the break 59 and the change from the upward movement of the rack 27 to the downward movement is made without any shock and without any danger of breaking the gear teeth.

100 In a like manner the segment 46 makes connection with the rack 26, and when the motion is reversed and the rack 24 up and ready to start down the spring catch tooth 66 makes connection with the rack 24.

105 The segment 32 of the mutilated gear 31 overlaps at both ends with the segments 33 and 34, thus producing the long gear teeth 78, 79, 80 and 81 at one end of the segment 32 and the corresponding ends of the segments 33 and 34, and similar long teeth 82, 83, 84 and 85 at the opposite ends of the three segments. The result is an overlapping movement of the pump rods 21 and 22. When the mutilated gear 31 is in the position 110 approximately as shown in Fig. 4, the segments 33 and 34 are lifting the racks 26 and 27 and are near the upper ends of the movements of the racks, and before the extreme upper movement ceases the segment 32 takes hold of the rack 24, and during the travel of the gear teeth 85, 84, 83 and 82 all three racks are moving upwardly at the same time, thereby lifting both of the pump rods 21 and 22 at the same time. Then as the teeth 115 82 go out of mesh with the racks 26 and 27

the rack 24 proceeds upon the upward movement while the racks 26 and 27 are reversed and lowered by the mutilated gear 41, and in the same manner when the mutilated gear 31 has made substantially a half revolution the rack 24 is near the end of its upward stroke and before the end of the upward stroke of the rack 24 is reached the gear teeth 78 take hold of the racks 26 and 27 and 19 start the upward stroke of said racks 26 and 27, and the result is a continuous even flow from the pump.

If it were not for these overlapping ends of the segments 32, 33 and 34 both pump rods 21 and 22 would come to a standstill and each end of their movements thus interrupting the flow twice at each complete cycle of the pump.

The column of water or oil flowing from 20 the pump will move continuously and uniformly at the rate of thirteen inches per second with a mutilated gear 31 revolving at the rate of thirty revolutions per minute. If it were not for the overlapping of the 25 segments the column of fluid would come to a standstill twice at each revolution of the gear 31, and twice at each revolution of this gear the machinery would come up against the dead load of the still column of fluid at 30 the rate of thirteen inches per second.

The pitch speed of the mutilated gear 41 is nearly twice the pitch speed of the mutilated gear 31, so that the racks will go down and the pump rods will go down nearly twice 35 as fast as they go up, and the weight of the descending pump rod is hung upon the periphery of a gear nearly twice as large as the gear upon which the ascending pump rod is hung, so that the weight of the descending 40 pump rod will assist in counterbalancing the weight of the ascending pump rod carrying the load of the column of fluid.

Thus I have produced a double acting long 45 stroke pump head providing a continuously uniform flow having few and strong durable parts, easily assembled, easily made and easily repaired.

Various changes may be made without departing from the spirit of my invention as 50 claimed.

I claim:

1. The combination with a double acting pump having an inner pump rod and an outer pump rod, of a gear rack connected to 55 the inner pump rod, mating gear racks connected to the outer pump rod one on each side of the first gear rack, a mutilated gear adapted to mesh alternately with the gear rack connected to the inner pump rod and 60 the gear racks connected to the outer pump rod as required to raise the gear racks to operate the pump rods upwardly alternately, a second mutilated gear adapted to mesh

with the gear rack connected to the inner pump rod and the gear racks connected to 65 the outer pump rod alternately as required to lower the pump rods, and a driving shaft and gearing connecting the mutilated gears for continuous operation.

2. The combination with a double acting 70 pump having an inner pump rod and an outer pump rod, of a gear rack connected to the inner pump rod, mating gear racks connected to the outer pump rod one on each side of the first gear rack, a mutilated gear 75 adapted to mesh alternately with the gear rack connected to the inner pump rod and the gear racks connected to the outer pump rod as required to raise the gear racks to operate the pump rods upwardly alternately, 80 a second mutilated gear adapted to mesh with the gear rack connected to the inner pump rod and the gear racks connected to the outer pump rod alternately as required to lower the pump rods, a driving shaft, 85 gearing connecting the driving shaft and the mutilated gears for continuous operation, and means for accurately adjusting the geared connection between the two mutilated gears. 90

3. The combination with a double acting pump having an inner pump rod and an outer pump rod, of a gear rack connected to the inner pump rod, mating gear racks connected to the outer pump rod one on each side of the first gear rack, a mutilated gear 95 adapted to mesh alternately with the first gear rack and with the second gear racks to operate the pump rods upwardly alternately, a second mutilated gear adapted to mesh 100 with the first gear rack and with the second gear racks alternately as required to lower the pump rods, the second mutilated gear having bevel faced spring catch teeth to mesh with the gear racks at the beginning of 105 the downward movements, and a driving shaft and gearing connecting the mutilated gears for continuous operation.

4. The combination with a double acting pump having an inner pump rod and an 110 outer pump rod, of a gear rack connected to the inner pump rod, mating gear racks connected to the outer pump rod one on each side of the first gear rack, a mutilated gear having overlapping segments adapted to 115 mesh alternately with the first gear rack and with the second gear racks as required to overlap the movements of the pump rod and make a continuous operation of the pump, a second mutilated gear adapted to 120 mesh with the first gear rack and with the second gear racks as required to lower the pump rods alternately, and a driving shaft and gearing connecting the mutilated gears for continuous operation. 125

5. The combination with a double acting

4
pump having an inner pump rod and an outer pump rod, of a gear rack connected to the inner pump rod, mating gear racks connected to the outer pump rod one on each side of the first gear rack, a mutilated gear having overlapping segments meshing alternately with the first gear rack and the second gear racks, a second mutilated gear having segments adapted to mesh with the first gear rack and with the second gear

racks alternately, said segments having bevel faced spring catch teeth at their forward ends to snap into the gear racks at the beginning of their downward movements, and a driving shaft and gearing connecting the mutilated gears for continuous operation.

In testimony whereof I have signed my name to this specification.

CHARLES J. SCHENK
